UNITED STATES PATENT OFFICE.

AUGUSTUS L. ENGELBACH, OF LEADVILLE, COLORADO.

REVERSING-VALVE.

SPECIFICATION forming part of Letters Patent No. 434,328, dated August 12, 1890.

Application filed January 28, 1890. Serial No. 338,329. (No model.)

To all whom it may concern:

Be it known that I, AUGUSTUS L. ENGELBACH, of Leadville, in the county of Lake and State of Colorado, have invented a new and 5 Improved Valve for Steam-Engines, of which the following is a full, clear, and exact description.

The object of the invention is to provide a new and improved steam-engine valve which 10 is simple and durable in construction, very effective in operation, and permits of quickly reversing the engine at any time.

The invention consists of a slide-valve and a semi-cylindrical valve-seat, on which the said 15 slide-valve operates and which is mounted to be turned in the steam-chest.

The invention also consists of certain parts and details and combinations of the same, as will be hereinafter fully described, and then 20 pointed out in the claims.

Reference is to be had to the accompanying drawings, forming a part of this specification, in which similar letters of reference indicate corresponding parts in all the figures.

25 Figure 1 is a sectional side elevation of the improvement as applied. Fig. 2 is a transverse section of the same, on the line xx of Fig. 1. Fig. 3 is a plan view of the steam-chest and cylinder. Fig. 4 is a plan view of the valve-seat. Fig. 5 is an inverted plan view of the same. Fig. 6 is a transverse section of the same on the line yy of Fig. 4. Fig. 7 is a like view of the same on the line zz of Fig. 4, and Fig. 8 is a similar view of the same on 30 the line ww of Fig. 4.

In the steam-engine cylinder A, is held to slide, in the usual manner, the piston B, secured on the piston-rod C. On the top of the cylinder A is arranged a steam-chest D, provided 40 with a semi-cylindrical bottom E, in which is held to turn the similarly-shaped valve-seat F, on the flat top of which is mounted to slide longitudinally a slide-valve G, held in place at the sides by the ribs and flanges F', 45 projecting from the sides of the valve-seat F. The slide-valve G is provided at its under side with the usual cavity G', and receives a sliding motion by being connected with the valve-stem H by means of collars I, fitting 50 against the raised ends of the slide-valve G, so as to permit the latter to change its position sidewise without interfering in the least

with the position of the stem H. The latter receives its motion, by suitable means, in the usual manner, from the main driving-shaft of 55 the engine.

In one end of the valve-seat F is secured a shaft J, which extends in an opposite direction to the valve-stem H, and is placed in axial line with the latter. The short shaft J 60 passes through suitable stuffing-boxes in the end of the steam-chest D, and carries on its outer end a lever K, on which is pivoted a small hand-lever L, connected with a pin N, held to slide in the lever K, and adapted to 65 engage one of the apertures O' and O², formed in the segmental plate O, secured by a suitable bracket or other means to the top of the steam-chest D. As shown in Fig. 2, the pin N engages the aperture O', and when live steam 70 is admitted to the steam-chest D the engine runs in one direction; but when the operator desires to reverse the engine he presses on the lever L, so as to disengage the pin N from the aperture O', and moves the lever K in 75 the direction of the arrow X until the pin N registers with the aperture O² and engages the latter, so that the lever K is locked in place.

The arrangement of the several ports is as 80 follows: From the outer end of the cylinder A, at one side, leads a port a, which extends under the semicircular bottom E of the steam-chest D, and connects with the interior of the latter by ports a' and a², extending in line 85 with each other, as is plainly shown in Fig. 3. From the inner end of the cylinder A

leads a port b, which extends longitudinally under the semicircular bottom E of the said chest D, and connects with the latter by the 90 ports b' and b², located opposite the ports a² and a', respectively, and extending in line with each other. The ports a' and b² are adapted to register alternately, according to the direction in which it is desired to run the 95 engine, with the ports c' and c², formed in the under side of the valve-seat F and leading to the port c', leading to the top of the valve-seat, and over which operates the slide-valve G. Over the ports a² and b' operate 100 the ports d² and d', respectively, also formed in the valve-seat F and leading to a common port d, extending to the top of the seat F, and over which operates the slide-valve G.

Between the ports *c* and *d* in the seat *F* is arranged the exhaust-port *e*, which extends from the top of the valve to one side, to connect with a port *f*, leading to the exhaust-pipe *Q*, over which is arranged the steam-inlet pipe *P*, leading to the top of the steam-chest *D*. The slide-valve *G* in its forward and backward motion alternately connects the port *c* with the port *e* and the port *d* with the port *e* in order to exhaust.

The operation is as follows: When the lever *K* engages with its pin *N* the aperture *O'* in the segmental plate *O*, then the valve-seat *F* stands in the position shown in Fig. 2, in which the port *c²* registers with the port *b²*, while the port *c'* is closed. At the same time the port *d²* registers with the port *a²*, while the port *d'* is closed. Now, when the steam is admitted through the inlet-pipe *P* into the interior of the steam-chest *D*, then the steam first passes through the port *c* (see Fig. 1) and the port *b²* into the port *b* and to the inner end of the cylinder, thus exerting pressure against the piston *B* and forcing the same in the inverse direction of the arrow *X'*. The exhaust in front of the piston *B* takes place through the port *a*, the port *a²*, the port *d²*, and the port *d*, and from the latter past the cavity *G'* in the slide-valve *G* to the exhaust-port *e*, which latter at all times connects with the exhaust-port *f*, leading to the exhaust-pipe *Q*. Before the piston *B* has reached the end of its stroke the position of the slide-valve *G* changes, so that the port *d* becomes uncovered and steam from the steam-chest now passes through the ports *d* and *d²*, through port *a²* into the longitudinal port *a*, which leads to the outer end of the cylinder, so that the piston *B* is forced on its return-stroke in the direction of the arrow *X'*. The exhaust at the other side of the piston now takes place through the ports *b b² d² d*, the cavity *G'* in the slide valve *G* to the exhaust-port *e*, and through the port *f* to the exhaust-pipe *Q*. Now, when the operator desires to reverse the engine at any time he simply changes the position of the lever *K*, as above described, so that the valve-seat *F* turns in the bottom *E* of the steam-chest *D*, carrying with it the slide-valve *G*, which now remains connected with its valve-stem *H*, as the axis of the movement of the valve-seat *F* is in line with the axis of the valve-stem *H*. Thus the slide-valve *G* does not necessarily interrupt its travel while the reversing takes place. The changing of the valve-seat *F* connects the port *d'* with the port *b'* and the port *c'* with the port *a'*, while the ports *d²* and *c²* remain closed. Steam from the steam-chest *D* now passes, when the several parts are in the position shown in Fig. 1, through the port *c*, the port *c'* to the port *a'*, which leads the steam to the outer end of the cylinder, so as to force the piston *B* in the direction of arrow *X'*. When the position of the valve *G* changes, then the steam passes through the ports *d, d'*, and *b'* into the longitudinal port *b* and to

the inner end of the cylinder *A*. The exhaust takes place in a similar manner through the same ports, only in reverse order. Thus it will be seen that by merely changing the position of the valve-seat *F* the engine is reversed without interrupting even the movement of the slide-valve *G*.

Having thus described my invention, what I claim as new, and desire to secure by Letters Patent, is—

1. In a valve for steam-engines, the combination, with a slide-valve, of a valve-seat mounted to turn in the steam-chest to adapt its upper face upon which the said valve slides to be set at an angle, substantially as described.

2. In a valve for steam-engines, a semicircular valve-seat provided with double sets of inlet-ports and mounted to turn in the steam-chest, substantially as shown and described.

3. In a valve for steam-engines, the combination, with a semicircular valve-seat provided with double inlet-ports, a single exhaust-port, and mounted to turn in the steam-chest, of an ordinary slide adapted to travel on the flat top of the said valve over the said ports, substantially as shown and described.

4. In a valve for steam-engines, the combination, with the ordinary slide-valve and a valve-stem loosely connected with the said slide-valve, of a semicircular valve-seat on which the said slide-valve is mounted to slide, the axis of the said valve-seat being in line with the said valve-stem, substantially as shown and described.

5. In a valve for steam-engines, the combination, with the ordinary slide-valve and a valve-stem loosely connected with the said slide-valve, of a semicircular valve-seat on which the said slide-valve is mounted to slide, the axis of the said valve-seat being in line with the said valve-stem, and ribs or flanges extending longitudinally on the sides of the said valve-seat to hold the said slide-valve in place, substantially as shown and described.

6. In a valve for steam-engines, the combination, with the ordinary slide-valve and a valve-stem loosely connected with the said slide-valve, of a semicircular valve-seat on which the said slide-valve is mounted to slide, the axis of the said valve-seat being in line with the said valve-stem, the valve-seat being provided with an exhaust-port and two sets of inlet-ports, substantially as shown and described.

7. In a valve for steam-engines, the combination, with the ordinary slide-valve and a valve-stem loosely connected with the said slide-valve, of a semicircular valve-seat on which the said slide-valve is mounted to slide, the axis of the said valve-seat being in line with the said valve-stem, the said valve-seat being provided with an exhaust-port and two sets of inlet-ports, and means, substantially as described, for shifting the position of the said valve-seat, as set forth.

8. The combination, with a cylinder provided with two inlet-ports leading from opposite ends of the cylinder and each having two branch ports arranged in line with each other, and a steam-chest having a segmental bottom into which open the two branch ports, of a semicircular valve-seat fitted into the semicircular bottom of the said steam-chest and provided with inlet-ports, each having two branch ports adapted to alternately register with the branch ports of the cylinder-ports, substantially as shown and described.

9. The combination, with a cylinder provided with two inlet-ports leading from opposite ends of the cylinder and each having two branch ports arranged in line with each other, and a steam-chest having a segmental bottom into which open the two branch ports, of a semicircular valve-seat fitted into the semicircular bottom of the said steam-chest and provided with inlet-ports, each having two branch ports adapted to alternately register with the branch ports of the cylinder-ports, and a slide-valve held to slide on the top of the said valve-seat and provided with the usual cavity for connecting the said inlet-ports alternately with the exhaust-port in the said valve-seat, substantially as shown and described.

10. The combination, with a cylinder provided with two inlet-ports leading from opposite ends of the cylinder and each having two branch ports arranged in line with each other, and a steam-chest having a segmental bottom into which open the two branch ports, of a semicircular valve-seat fitted into the semicircular bottom of the said steam-chest and provided with inlet-ports, each having two branch ports adapted to alternately register with the branch ports of the cylinder-ports, substantially as shown and described.

branch ports of the cylinder-ports, a slide-valve held to slide on the top of the said valve-seat and provided with the usual cavity for connecting the said inlet-ports alternately with the exhaust-port in the said valve-seat, a shaft extending from one end of the said valve-seat and having its axis in line with the stem of the slide-valve, and a lever held on the outer end of the said shaft for changing the position of the said valve-seat, substantially as shown and described.

11. The combination, with a cylinder provided with two inlet-ports leading from opposite ends of the cylinder and each having two branch ports arranged in line with each other, and a steam-chest having a segmental bottom into which open the two branch ports, of a semicircular valve-seat fitted into the semicircular bottom of the said steam-chest and provided with inlet-ports, each having two branch ports adapted to alternately register with the branch ports of the cylinder-ports, a slide-valve held to slide on the top of the said valve-seat and provided with the usual cavity for connecting the said inlet-ports alternately with the exhaust-port in the said valve-seat, a shaft extending from one end of the said valve-seat and having its axis in line with the stem of the slide-valve, a lever held on the outer end of the said shaft for changing the position of the said valve-seat, and means, substantially as described, for locking the said lever in place when shifted, substantially as shown and described.
